UNITED STATES PATENT OFFICE

EMORY E. JONES, OF BLUEFIELD, WEST VIRGINIA, ASSIGNOR TO WINDING GULF
COLLIERIES, OF BLUEFIELD, WEST VIRGINIA

COAL BRIQUETTING EQUIPMENT

Application filed December 15, 1931. Serial No. 581,228.

The device forming the subject matter of this application is adapted to be used for making briquettes of the kind which are composed of finely divided coal, and a binder, such as asphalt.

One object of the invention is to provide novel means for securing a uniform flow of the mixture toward the briquetting rolls. Another object of the invention is to improve the construction of the gate which regulates the flow of the mixture to the briquetting rolls. A still further object of the invention is to supply novel means for operating the gate.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:—

Fig. 1 shows, in side elevation, a machine constructed in accordance with the invention;

Fig. 2 is a section on the line 2—2 of Fig. 1;

Fig. 3 is a top plan, wherein parts are broken away;

Fig. 4 is a transverse section of the complete machine, most parts being in elevation;

Fig. 5 is a view wherein the gate appears edgewise;

Fig. 6 is a top plan of the gate;

Fig. 7 is an end elevation of the gate. As an adjunct to the invention claimed, there is provided a mixing device 1, discharging finely divided coal.

A box-like hopper-head 10 is secured to the mixing device 1, about the outlet 6. The hopper-head 10 comprises a forward wall

11 which is downwardly and rearwardly inclined.

After the coal and the asphalt binder have been mixed in the mixing device 1, the material passes through the outlet 6 and is received on the wall 11 of the hopper-head 10, and moves into a hopper 14, which is secured to the lower end of the head 10. The hopper 14 is arranged vertically, or nearly so. Fig. 2 shows that the hopper 14 is of rectangular cross section. The hopper 14 has a slidably mounted, vertically adjustable wall 15, under the control of an adjusting means, such as a headed screw 16, journaled in the projecting edge of the top of the hopper-head 10, and threaded into an outstanding lip on the upper end of the wall 15. Fig. 2 shows that the vertical internal corners of the hopper 14 are rounded and concaved, as shown at 17.

In order that briquettes of even hardness and uniform quality may be made, it is necessary to feed the mixture evenly to the briquetting press, hereinafter described. A feed that is heavier or harder near to the center of the press than at the sides of the press will cause the briquettes to be made too hard at the center and too soft around the periphery, a briquette of uneven texture, as to hardness, being an article which a discriminating trade will reject. Because the internal vertical corners of the hopper 14 are rounded or concaved, as shown at 17 in Fig. 2, there is no tendency for the mixture to stick and build up in the corners, as the mixture moves downwardly through the hopper 14. The friction at the corners, therefore, is not greater than elsewhere, the mixture flows down evenly, and a uniform feed to the briquetting press, and more especially to the gate, hereinafter described, results.

Carried by the frame 18 of the briquetting press are vertical plates 19, and on the inner surfaces of the plates there are downwardly and inwardly inclined guides 20. The numeral 21 designates a slidably mounted gate, adapted to move along the downwardly and inwardly inclined lower edge 22 of the hopper 14, so as to regulate

the space between the inner edge of the gate and one of the rolls 23 of the briquetting press. Fig. 7 shows that there are recesses 24 in the upper surface of the gate 21, at 5 the outer edges thereof. In the recesses 24, side pieces 25 are mounted for longitudinal adjustment, the upper surfaces of the side pieces being flush with the upper surface of the gate 21. The lateral portions 10 of the gate 21 and the outer edges of the side pieces 25 are slidably received in the guides 20. The inner ends of the side pieces 25 are cut away and rounded, as shown at 26, and it may therefore be said 15 that the gate 21 is cut away at its inner corners, to leave openings at the inner corners of the gate, adjacent to the periphery of the roll 23 of the briquetting press. Securing elements 27, such as bolts, are 20 mounted in the lateral portions of the gate 21, and are received in elongated slots 28 formed in the side pieces 25 of the gate. By loosening the bolts 27, the side pieces 25 may be adjusted in and out, with respect 25 to the roll 23, to vary the size of the openings at the inner corners of the gate 21, adjacent to the periphery of the roll 23. The gate 21 slides in alignment with one of 30 the prolonged diameters A—B of the roll 23, as shown in Fig. 1. Because the wall 15 of the hopper 14 is vertically adjustable, through the instrumentality of the means shown at 16, the wall 15 may be made to 35 cooperate properly with the upper surface of the gate 21.

Because the gate 21 is adjustable in and out, in line with the diameter A—B of the roll 23, the gate is disposed at right angles to the mixture, as the mixture flows downwardly across the inner edge of the gate, and the resistance offered to the downward movement of the mixture can be regulated, as the gate 21 is moved in and out, better than would be the case if the gate were 45 disposed otherwise than in line with the axis A—B. Since the side members 25 of Fig. 6 can be adjusted in and out, the distance between the inner ends of the side members and the periphery of the roll 23 50 can be adjusted, and the friction of the downwardly moving material at the sides of the hopper 14 can be regulated, thereby bringing about an even downward flow of the mass of material at the sides of the mass 55 and at the center of the mass, the material being distributed uniformly and fairly to the rolls 23 and 29 of the briquetting press.

The rolls 23 and 29 of the briquetting press have the usual cups 30 for the formation 60 of the briquettes, and the driving mechanism 31 for the rolls may be of the usual intermeshing-gear construction indicated in Fig. 3, and calling for no extended description.

Any suitable means may be provided for

adjusting the gate 21 in and out. Thus, as shown, but not of necessity, a link 32 is connected by a removable pivot element 33 with the outer edge of the gate 21, the link being pivoted to an arm 34 on a shaft 35 mounted to rock in a segment 36 on a support 37, a hand lever 38 being secured to the shaft 35, and the hand lever carrying latch mechanism 39, adapted to cooperate with the segment 36. 75

The operation of the press has been dealt with hereinbefore, step by step, but by way of résumé, it may be stated that the divided coal and the binder are introduced into the hopper-head 10 by the mixing device 1. The mixed material moves downwardly through the hopper 14, across the inner edge of the gate 21, and the briquetting is brought about by the cupped rolls 23 and 29 of the press, these rolls being rotated by the mechanism shown in Fig. 3 at 31. 80

The inward and outward movement of the gate 21, by means of the hand lever 38 and associated parts, need not be gone into, since it will be understood readily when Fig. 1 of the drawings is casually inspected. 90

Having thus described the invention, what is claimed is:—

1. A coal briquetting press embodying 95 cooperating rolls journaled for rotation, a hopper above and discharging between the rolls, and a gate slidable at the lower end of the hopper, at an acute angle to the line of flow through the hopper, the inner corners of the gate being cut away, adjacent to one roll, and at the sides of the hopper. 100

2. A coal briquetting press embodying 105 cooperating rolls journaled for rotation, a hopper above and discharging between the rolls, and a gate slidable at the lower end of the hopper, at an acute angle to the line of flow through the hopper, in alignment with a prolonged diameter of one roll, the inner corners of the gate being cut away, adjacent to said roll, and at the sides of the hopper. 110

3. A coal briquetting press embodying 115 cooperating rolls journaled for rotation, a hopper above and discharging between the rolls, and a gate slidable at the lower end of the hopper, toward and away from one roll, side pieces adjustable on the gate, toward and away from said roll, and means for holding the side pieces in adjusted positions on the gate, thereby to leave spaces at the inner corners of the gate, adjacent to said roll, and at the sides of the hopper. 120

In testimony that I claim the foregoing as my own, I have hereto affixed my signature.

EMORY E. JONES.
